INTERNAL COMBUSTION ENGINE

Hyman Policansky, Cape Town,
Union of South AfricaApplication October 22, 1935, Serial No. 46,099
In Great Britain October 26, 1934

4 Claims. (Cl. 123—14)

This invention relates to internal combustion engines and more particularly to internal combustion engines of the kind comprising an outer casing or stator constructed to form within itself an annular chamber, a rotor mounted to rotate within said casing and having one or more vanes adapted to move within said annular chamber, shutters adapted to be moved into and out of the path of the said vanes to portion the annular chamber into separate compartments such as a compression chamber and a combustion chamber, inlet and exhaust ports to said annular chamber, transfer ports for transferring the charge compressed from a compression chamber formed in front of one of said vanes to a combustion chamber formed behind said vane and means for igniting said charge.

One of the objects of the present invention is to provide an improved construction of transfer passage and co-operating scavenging member. A further object of the invention is to provide means whereby the force urging the scavenging member into co-operation with said transfer recess increases with the speed of the engine.

One embodiment of the invention is illustrated in the accompanying drawings wherein:

Figure 1 is a part sectional elevation of one form of internal combustion engine made in accordance with the present invention.

Figure 2 is a cross section on the line 2—2 on Fig. 1 and looking in the direction of the arrow.

Figure 3 is a developed part sectional view of the engine shown in Fig. 1, the section being taken on the line 3—3 and looking in the direction of the arrow.

Figure 4 is a developed sectional view on the line 4—4 on Fig. 1 looking in the direction of the arrow.

Figure 5 is a detailed elevation of the rotor seen in Fig. 1.

Figure 6 is a sectional view substantially similar to Fig. 2 showing the mechanism for operating shutters 67 and 68.

In the form illustrated in the drawings the engine comprises a stator A formed by two circular disc-shaped sides 10 and a cylindrical portion 11 bolted or otherwise secured together.

The sides 10 are each formed with circular concentric ribs 12 and said sides 10 and cylindrical portion 11 enclose an annular chamber 13 having a groove 14 centrally disposed on the perimeter of the said annular chamber 13, said groove being formed between the inwardly projecting concentric ribs 12. Journalled concentrically in the two sides 10 is a shaft 15 having splines 16 on which

is mounted the rotor 17 and cams 18 and 19. The rotor 17 is formed with spokes 20, a concentric ring 21, and vanes 22 and 23 mounted on the periphery of the ring 21. The ring 21 is shaped to coact with the circular concentric ribs 12 and close the groove 14. The sides 10 and the cylindrical portion 11 are slotted at 24, 25, 26 and 27. In the sides 10 and positioned just after the groove 27 are inlet ports 28 and just before the groove 24 are positioned twin exhaust ports 29. Diametrically opposed to the ports 28 and 29 are inlet ports 30 and exhaust ports 31. Positioned just after the grooves 24 and 25 are sparking plugs 32 and 33 screwed in to threaded holes in the cylindrical portion 11. Immediately adjacent the exhaust port 29 but just before this is a port 34 controlled by a mushroom valve 35, which is held on its seat by a spring 36, the tension of which is adjustable by means of the thumb screw 37 carried on the end of the valve stem 38 which is threaded to receive it. The valve stem 38 is mounted in a guide 39 carried by a casting 40 bolted to the cylindrical portion 11 by bolts 41, the casting 40 forming a valve pocket and having a conduit 42 to receive gases discharged through the port 34 when the valve 35 is lifted off its seat.

The cylindrical portion 11 is also formed with two transfer recesses 43 and 43a which serve the purpose of transfer ports. The compression vane 23 is formed with a forwardly directed tapered head 44 and a tapered tail 45. On each side of the vane are positioned packing glands or compression retaining members 46—46. The vane 22 is provided with a scavenging member 47 projecting from a groove 48 in the top of the vane, said scavenging member 47 being carried on an arm 49 pivoted to the vane at 50 and urged outwardly by a spring 50a. When the rotor 17 is revolving with any appreciable speed the scavenging member 47 will be acted on by centrifugal force which will operate to assist the spring 50a and augment the pressure of the scavenging member 47 against the cylinder wall 11 so that as the speed of the engine increases, the force urging the scavenging member 47 into the transfer recess will also increase. The vane 23 has no scavenging member. Lugs 51 on the outside of the sides 10 are slotted in line with the slots 24 to form guides 52 for shutters adapted to be moved into and out of the path of the vanes 22 and 23. The tapering head and tail portions 44 and 45 respectively of the compression vane 23 enable a close association to be maintained between these shutters and the vane, whilst the shutters are opening and closing to allow the vane to pass.

A pair of shutters 53, 53, disposed in the guides 52 are arranged so that each is adapted to be projected half way across the annular chamber 13. Each shutter 53 is formed with a stepped end 54, 5 the stepped ends 54 overlapping each other when the shutters are together forming a gas seal. The shutters 53 are also formed with a port 55, the purpose of which will be described hereafter, and a slot 56 in which is positioned a pin 57 carried on the end of a cranked lever or rocker 58, the rocker 58 being mounted on a pivot 59 carried in bearings on the sides 10. Tappets 60 mounted in guides 61 in the sides 10 coact with the other end of the rockers 58 to open the shutters 53. Springs 62 urge the shutters 53 towards the closed position.

Similar lugs 63, 64 and 65 are provided in line with the slots 25, 26 and 27 respectively to accommodate pairs of shutters 66, 67 and 68 (see Figs. 20 3 and 4). The shutters 66 are operated by rockers and tappets exactly similar to the mechanism for operating the shutters 53 (see Fig. 2).

In Fig. 6 the mechanism for operating the shutters 67 is shown. As this is substantially similar 25 in construction and operation to the mechanism shown in Fig. 2 for operating the shutters 53 the same reference letters have been used wherever possible. The shutters 68 are diametrically opposed to the shutters 67 and their construction 30 and arrangement are identical therewith and will be clearly understood from Fig. 6. It will be appreciated that the shutters 53 and 66 are controlled by the cams 18 whilst the shutters 67 and 68 are controlled by the cams 19.

35 The passages 69, 70, 71 and 72 leading from the ports 28, 29, 30, and 31 respectively are formed in the lugs 51, 63, 64, and 65, and are curved towards the adjacent shutter guides in the respective lugs and are intersected thereby. As already 40 stated, the shutters 53 are provided with ports 55. The shutters 66, 67 and 68 are provided with similar ports 73, 74 and 75, the said ports 55, 73, 74, and 75 co-operating with the passages 69, 70, 71, and 72 to close said passages when the 45 shutters are open and vice versa.

The operation of the engine will now be described.

For the sake of simplicity, we will first follow the induction, compression, explosion, and exhaust of one charge without referring to what is taking place elsewhere in the engine.

In the position shown in Fig. 1 the inlet ports 28 are closed and corresponding shutters 68 are open. The exhaust ports 29 are open and corresponding shutters 53 closed. The inlet ports 30 are open and the corresponding shutters 67 are closed. The exhaust ports 31 are closed and the corresponding shutters 66 are open. Starting from this position the rotor 17 rotates counter-clockwise in the direction of the curved arrow. As the vane 22 passes the shutters 68 the said shutters 68 close behind the vane 22, the necessary force being supplied by the springs 62. As the shutters 68 close the inlet ports 28 open by 65 reason of the ports 75 and the shutters 68 coming into register with the passages 69 (see Fig. 3).

After the shutters 68 have closed and as the vane 22 continues to move in the direction of the curved arrow, explosive mixture is drawn through 70 the inlet ports 28 into the enlarging space formed between the shutters 68 and the vane 22. The induction stroke continues until the shutters 68 open to allow the passage of the vane 23 thus closing the inlet ports 28, the vane 22 having in 75 the meantime passed the shutters 53 which open

just before it reaches them, and passed on to the shutters 67 which are already open.

As the vane 22 passes the recess 43 the scavenging member 41 in the vane 22 enters the said recess in order to allow the induction stroke 5 to continue. The vane 22 then passes the shutters 67, which close behind it, and the charge of explosive gas induced by the vane 22 is trapped between shutters 67 and vane 23, which has now passed the shutters 68. As the vane 23 approaches the shutters 67, the gas is compressed in that portion of the annular chamber 13 and the compression continues until the vane 23 has passed the shutters 53 which close behind it and reaches the transfer recess 43. The greater part 15 of the compressed charge is then allowed to escape past the vane 23 into the chamber enclosed behind the vane 23 between it and the shutters 53. The transference of gas past the vane 23 continues until the body of the vane 23 reaches 20 the end of the transfer recess, whereupon a spark is caused to take place at the points of the plug 32. Explosion of the ignited gas impels the vane 23 forward, the shutters 67 in the slots 26 opening to allow the vane 23 to pass and the explosion stroke continues until the vane 23 passes 25 the shutters 66 which close immediately behind the vane. The burnt gases are thus trapped between the shutters 66 and the vane 22 which has now again passed the shutters 53, the approach 30 of the vane 22 expelling the burnt gases through the exhaust ports 31 opened by the closing of the shutters 66. It will be understood that whilst the vane 23 is compressing the gas induced through the port 28 against the shutters 67 in the slots 26, 35 the vane 22 is inducing gas through the port 30 just opened by the closing of the shutters 67 and the explosion of the charge between the vane 23 and the shutters 53 causes the vane 23 to compress the next charge against the shutters 68. 40

It will also be understood that whilst the burnt gases are being expelled from in front of the vane 22 a fresh charge is being induced behind the vane 22. In each revolution of the rotor the vane 23 during the compression stroke passes the port 34 which is controlled by the mushroom valve 35. Part of the gas compressed against the shutters 68 in the slots 27 will not have been transferred past the vane 23, as it passes the transfer recess 43a. If the pressure of the compression is 50 greater than a predetermined amount, the valve 35 will lift against the spring 36 and allow some of the compressed gas to escape into the conduit 42 and thence back into the induction system (behind the stator A but not shown) of the 55 engine. After passing the port 34 the vane 23 will completely compress a charge in the usual way. The provision of the valve 35 prevents an excessive pressure from being produced in that part of the annular chamber 13 in which it is positioned if desired. Another similar valve may be provided in a diametrically opposite position so as to prevent excessive pressure from being generated in the other half of the annular chamber 13 when compression is taking place in that 60 65 half.

It will be clear that the tapering portion of the vane enables a close association to be maintained between the shutters and the vane whilst the shutters are opening and closing.

What I claim and desire to secure by Letters Patent is:—

1. In a rotary internal combustion engine of the kind having at least one vane adapted to move within an annular chamber, shutters 70 75

- adapted to be moved into and out of the path of said vane and at least one transfer recess in said annular chamber, a scavenging member carried by said vane and adapted to co-operate with said transfer recess, said scavenging member comprising an arm pivotally mounted on said vane and disposed in a recess therein and means for causing said scavenging member to be projected so as to co-operate with and enter said transfer recess.
2. In a rotary internal combustion engine of the kind having at least one vane adapted to move within an annular chamber rectangular in cross section and shutters adapted to be moved into and out of the path of the said vane, walls to said annular chamber one being a cylindrical wall at least one transfer recess formed in the cylindrical wall and a scavenging member carried by said vane and adapted to co-operate with said transfer recess.
3. In a rotary internal combustion engine of the kind having at least one vane adapted to move within an annular chamber rectangular in cross section and shutters adapted to be moved into and out of the path of the said vane, walls to
- said annular chamber one being an outer cylindrical wall at least one transfer recess formed in said outer cylindrical wall, and a scavenging member carried by said vane and mounted for radial movement thereon whereby said scavenging member is urged in a radial direction by centrifugal force into co-operation with said transfer recess.
4. In a rotary internal combustion engine of the kind having at least one vane adapted to move within an annular chamber rectangular in cross section and shutters adapted to be moved into and out of the path of the said vane, walls to said annular chamber one being a cylindrical wall, at least one transfer recess formed in said cylindrical wall, a scavenging member carried by said vane and adapted to co-operate with said transfer recess, spring means for urging said scavenging member into co-operation with said transfer recess and means for causing centrifugal force to act on said scavenging member and assist said spring means.

HYMAN POLICANSKY.
